CLAIM

The ornamental design for a lock box, as shown and described.

DESCRIPTION

FIG. 1 is front elevational view of the lock box, shown with the access door in the open position;

FIG. 2 is a rear elevational view thereof;

FIG. 3 is a right side elevational view thereof, the left side elevational view being a mirror image thereof;

FIG. 4 is a top plan view thereof; and,

FIG. 5 is an upper perspective view thereof.

The bottom view of the lock box is entirely disclaimed.

The portions of the lock box shown in broken lines are for illustrative purpose only and form no part of the claimed design.
